FLOYD L. SCOTT, OF HOUSTON, TEXAS, ASSIGNOR TO HUGHES TOOL COMPANY, OF
HOUSTON, TEXAS, A CORPORATION OF TEXAS

EARTH BORING DRILL

Application filed March 12, 1929. Serial No. 346,308.

My invention relates to drills for drilling wells for water, oil, gas and the like. It pertains particularly to drills adapted for use in softer types of formation although not limited to soft formation drills.

In drilling deep wells, there is usually a limit to the load which the careful driller will allow to rest upon the drill in its operation. This is true, particularly, where the walls of the well are soft, or of crumbly structure upon which the flushing fluid acts to form ruts or fissures. When this happens, the walls of the well will not support the drill stem when said drill stem tends to bend. The driller is then afraid to allow the full weight of the drill stem to rest upon the drill, for if he does, the drill stem will be bent by the weight above and will be seriously damaged. The driller will, therefore, suspend a portion of the weight of the drill stem from the crown block of the derrick, and allow only a safe load to rest upon the drill.

The drill is driven into the formation being drilled by the weight placed thereon, and sometimes the safe load which may be used is insufficient to force the blades of the drill into the formation an amount sufficient to obtain the best results for speedy and economical drilling.

It is an object of my invention to provide a drill bit with the smallest practical amount of cutting edge so that the weight resting thereon will be most effective in driving it into the bottom of the well. I desire to limit the amount of cutting edge so that the available weight will be distributed over a smaller amount of cutting area, and thus obtain greater penetration.

I aim to cut the outer area of the bottom of the well in an annular path, leaving the center uncut; and then to break off and shatter the core projecting up from the well bottom without the necessity of drilling that portion.

The invention resides in the particular construction of the drill whereby these objects may be accomplished and in the manner in which the hole is drilled.

Referring to the drawings herewith, Fig. 1 is a vertical section through a drill

embodiment of my invention, said section being on the plane 1—1 of Fig. 3.

Fig. 2 is a side elevation of the tool.

Fig. 3 is a bottom plan view of the same.

The drill is formed with a head 1 of circular formation but tapering somewhat downwardly. It has a central threaded socket 2 to connect with a drill collar or tool joint 3 for operation.

The head is provided with an opening 4 through the lower end for flushing fluid. Across this opening are a plurality, preferably three, approximately radial arms or blades 5, joined together centrally of the opening and connected with the side rim of the opening at their outer ends. Said blades are for breaking up the core and are not for drilling. The blades are inclined slightly forward in the direction of rotation of the drill, as will be noted from Fig. 3, and have the forward side provided with a core engaging edge 6.

The cutters for the drill comprise a plurality of laterally extending blades 7, said blades extend outwardly from the head 1 and project materially in advance of the head. The blades are inclined forwardly in the direction of rotation and the forward side is formed with a vertical cutting edge 8 and a lower cutting edge 9, said lower edge being inclined downwardly as seen in Figs. 1 and 2.

Adjacent the lower ends of the blades, a reinforcing ring 10 connects their inner edges and the lower cutting edge is extended below said ring 10 to cut clearance therefor as seen at 11.

It will be noted that the drill thus assumes the appearance of a soft formation core drill in that it does not cut the center of the hole inside the ring 10. The core which will project up into the ring will be broken up, however, by the breaking arms 5. The breaking up of the core is easily accomplished as the core is entirely unsupported from the outside. The arms 5 act to split off chunks and fragments from the upper end of the core and said fragments are carried away by the flushing fluid to the surface.

Practically the entire weight of the drill may thus rest upon the cutting edges 9 of the

blades and the cutters will be more effectively forced to penetrate the formation at the bottom of the hole. The ordinary safe weight which may be employed in drilling will thus be entirely sufficient for economical operations.

What I claim as new is:

- A rotary well drill including a downwardly tapered tubular head, forming an inner 10 tapered socket threaded for connection with a drill stem, cutting blades thereon projecting laterally from said head and curved forwardly in the direction of rotation, said 15 blades extending materially in advance of said head means connecting the forward ends of said blades, and short core breaking blades extending inwardly from said cutting blades and joined integrally together adjacent the forward end of said head.
- 20 In testimony whereof I hereunto affix my signature this 8th day of March A. D., 1929.

FLOYD L. SCOTT.
